OIL-REFINING FOLDABLE PACK

Albert R. White, Glendale, Calif.

Application August 22, 1944, Serial No. 550,612

1 Claim. (Cl. 210—131)

1

The present invention relates to improvements in an oil refining foldable pack and casing, and it consists of the combinations, constructions, and arrangements hereinafter described and claimed. This application is a continuation-in-part of my copending application on an oil refining foldable pack and casing, Serial Number 427,461, filed January 20, 1942, and now abandoned.

In the usual oil refiner packs and casings, the pack has a rigid central core and this requires the casing opening to be of a diameter equal to the diameter of the casing interior. If the oil refiner pack is constructed with a flexible core rather than with a rigid one, it is possible to make the casing opening smaller and make the pack diameter equal to or even less than the casing opening. The pack can be fed into the casing and folded or coiled into place so as to fill any proportion of the casing interior desired. The foldability or flexibility of the pack not only adapts it to fill a casing which has a diameter larger than the diameter of the casing opening, but the pack may be placed in casings or containers having irregular shapes and sizes. For example, the container or housing may be curved, or one portion of the housing may be larger than another.

By providing an oil refining pack which is foldable or flexible I am able to make use of the usual oil tank or sump used in airplanes and cause it to perform an additional function of cleaning the oil in the tank. The tank becomes the casing for the pack and this does away with providing an extra casing and thus saves weight. Also the use of an airplane oil tank for housing the pack instead of using a separate casing will obviate the need of holding down brackets, bolts, nuts, fittings, and extra oil lines for the oil refiner. An oil refiner pack and casing is a necessity for an airplane to keep the oil clean, but where weight is at a premium, a refiner has frequently not been used. By employing the oil tank as the container for the foldable pack, the extra weight necessary for refining the oil is reduced to a small point because the pack itself is light in weight. The cover for the airplane oil tank is smaller in diameter than the tank, and the foldable oil refining pack can be threaded through the tank opening and placed in the tank in a spiral or any other fashion. The tank may be filled to any desired extent with the pack. The tank and pack therefore perform the double function of holding the oil and cleaning the oil. A by-pass is used with the oil refiner pack to permit the oil to flow freely through the tank should the pack become clogged for any reason.

One of the principal objects of my invention is to provide a foldable oil refiner pack in which a flexible central sustaining member has a density less than that of the pack proper and there-

2

fore the member acts as an oil conduit. The length and the diameter of the pack may be changed to accomplish any particular oil cleaning purpose and to fit any container of any size and shape. The pack provides the maximum amount of surface area compatible with the highest efficiency in depth of filtering material for any given diameter and length of filtering element. The invention is simple in construction.

Other objects and advantages will appear in the following specification, and the novel features of the device will be particularly pointed out in the appended claim.

My invention is illustrated in the accompanying drawings forming a part of this application, in which:

Figure 1 is a side elevation of the foldable pack and illustrates its attachment in an oil tank;

Figure 2 is a longitudinal section through the foldable pack, portions being shown in elevation;

Figure 3 illustrates the foldable pack placed in an oil tank or sump;

Figure 4 is a longitudinal section of a modified form of the invention, portions being shown in elevation;

Figure 5 is a longitudinal section through another modified form of the invention, portions being shown in elevation for clarity;

Figure 6 is a longitudinal section through still another modified form of the invention; and

Figure 7 is a transverse section taken along the line 7—7 of Figure 6.

While I have shown only the preferred forms of my invention, it should be understood that various changes or modifications may be made within the scope of the appended claim without departing from the spirit of the invention.

I will first describe the oil tank and then the pack.

Oil tank

In carrying out my invention I provide an oil tank or container, indicated generally at A, and this container may be of any shape or size desired. One type of container is illustrated in Figure 3 and is in reality a tank or sump used in an airplane for holding lubricating oil. I do not wish to be confined to the particular type of container shown in the drawing since it is given only by way of one example. The novel feature of the container is that it performs the double function of holding the lubricating oil and of holding the foldable pack that refines the oil. The container A has an oil inlet pipe 1 communicating therewith and the oil outlet pipe 2 that is normally used is closed by means of a plug 3. The container has a cover 4 of a smaller diameter than the diameter of the container or tank and the cover has one end of my foldable oil refining pack, indicated generally at B, attached thereto and communicating with an oil outlet pipe.

5. The pipe leads to the engine or other parts that need oiling and conveys the refined oil thereto while the pipe 1 conveys the used oil from the engine and other parts to the tank for storing and cleaning purposes.

Oil refining foldable pack

It is best now to describe the construction of the oil refining pack B. The pack is shown in detail in Figures 1 and 2 and it comprises a flexible core 6 which may be in the form of a coil spring, shown in Figure 2, or in any other form. I have shown two modified forms such as a rolled screen at 6a in Figure 4 and a perforated flexible conduit 6b in Figure 5. The modified forms of the pack shown in Figures 4 and 5 differ slightly from the form shown in Figures 1 and 2, and I will describe them more in detail hereinafter.

The flexible core composed of the coil spring 6 has one end inserted in an outlet pipe 1 and the spring is secured in place by any suitable fastening means such as by nails 8 that are passed through the pipe and screen and extend at right angles to each other; see Figure 2. Around the spring 6 I dispose a screen 9 and the screen may consist of one or more layers. The screen is held in place on the spring by a cloth casing 10 that also acts as an oil filtering medium. Figure 2 illustrates the screen 9 extending beyond the free end of the spring 6, the projecting portion of the screen being flattened as indicated. The cloth casing 10 covers the entire length of the screen 9 and has its free end pressed flat so as to contact the flattened portion of the screen. Around the cloth 10 I dispose one or more layers of a vegetable sponge such as a loofah sponge 11 and the sponge extends throughout the length of the fabric 10. The purpose of the sponge is to absorb water from the oil without absorbing oil. The sponge is connected to the pipe 1 by thick absorbent string 12 that is wrapped around the sponge and pipe, the wrapping extending an appreciable distance along both the pipe and the sponge. The heavy string winding 12 not only acts as a flexible securing means between the sponge and the pipe, but in addition acts as a filtering medium for the oil and also tends to deflect the oil into the body of the pack. The tendency of the oil to flow along the outer surface of the pipe 1 toward the screen 9 is prevented by the heavy string winding 12 and the string will act as an oil deflector for directing the oil into the body 13 of the pack. Any oil that does seep through the heavy string winding will be filtered and cleaned before it reaches the coil spring.

The opposite end of the coil spring 6 from the pipe 1 is enclosed by the screen 9, the fabric 10, and the loofah sponge 11, all of these elements extending beyond the end of the spring and being flattened as indicated in Figure 2. A second winding 14 of thick absorbent string encloses the flattened portions of the screen, cloth and sponge and secures these parts together. The heavy string winding 14 deflects any oil tending to move into the end of the central passage formed by the spring, into the body of the pack 13, and this prevents the immediate entrance of the oil into the central oil passage prior to its being filtered and refined. A number of layers of string make up the heavy string winding 14 and the same is true of the heavy string winding 12. The windings 12 and 14 can be regarded as flexible oil deflectors and as securing means for holding the parts together.

The pack 13 that surrounds the flexible core formed of the spring, screen, cloth and sponge may be made of any oil filtering and oil cleaning material desired. I prefer to use a material known as waste for the body of the pack. The diameter of the pack body may be made as large as desired and the coil spring 6 will act as a flexible central sustaining member for the pack. In addition, the screen, fabric and sponge provide a wall for a central oil passageway for the pack. The central passage has a less density than the density of the pack. Oil in passing through the pack and finding its way to the central passage will flow therealong in preference to flowing through the pack because the density is less. The central passage is open, as when using the spring 6, will convey the refined and filtered oil therealong. If the passage is formed from a conducting material, the material must be less dense than that forming the pack.

If desired the outer surface of the pack body 13 may be enclosed in a fabric casing 15 which will also act as an oil cleaning element. The fabric casing 15 is secured to the pack by a fine string 16 that is wrapped around the pack at each end, the string preferably being wrapped around the pack throughout its length in order to hold the fabric casing 15 in place while permitting the pack to be folded. Figure 1 illustrates the string 16 as being wrapped around the free end of the pack for holding the material 13 in place. The fabric casing 15 has its other end brought tightly around the pipe 1 and secured in place by the same string 16. In this way the pack is secured to the pipe 1 and yet the pack is flexible enough to be coiled, folded or arranged in any position in a container.

The particular means for securing the pipe 1 to the cover 4 of the tank A is illustrated in Figure 1. The pipe 1 has a metal flange 17 which holds an asbestos washer 18 against the underside of the tank cover 4. The pipe 1 extends through an opening 19 in the cover and receives a second asbestos washer 20 that bears against the outer side of the cover. A metal ring 21 is moved onto the pipe 1 and bears against the asbestos washer 20. A nut or sleeve 22 is threaded upon the threaded portion 23 of the pipe 1 and forces the ring 21 down upon the asbestos washer 20. A tightening of the sleeve will bring the flanges 17 and 21 toward each other for forming a liquid tight seal. The sleeve 22 may be grooved as at 22a and the ring 21 is made of a metal soft enough to have a portion thereof forced into the groove for aiding in making a liquid tight seal between the pack and the cover. The oil outlet pipe 5 connects with the sleeve 22, thus communicating with the pack B.

I provide a bypass valve C for the pipe 1; see Figure 1. The bypass functions automatically in case the pack becomes clogged. When the bypass is open, direct communication is established between the tank interior and the outlet pipe 5. The bypass comprises a nipple 24 which is screwed into a T 25 that forms a part of the pipe 1. The other end of the nipple is screwed into a valve casing 26 and holds a coil spring 27 against a ball valve 28. The ball is kept seated against the seat 29 in the casing until the pressure of oil in the tank A reaches a point sufficient to unseat the ball 28 and compress the spring 27. The valve body 26 has a plurality of openings 30 through which the oil flows to unseat the ball. The tension of the spring is varied by adjusting

the nipple 24 with respect to the casing 26 and in this way the valve may be adjusted to open at any predetermined pressure.

Operation

From the foregoing description of the various parts of the device, the operation thereof may be readily understood.

The container A, illustrated in Figure 3, can be partially filled or entirely filled with the oil refining pack B. The diameter of the pack is made less than the diameter of the opening 31 in the container so that the pack can be fed through the container opening and coiled within the container as indicated. By using a flexible pack the container can be filled by the pack to any desired extent, even though the container diameter is larger than the cover diameter. I do not wish to be confined to the particular type of container illustrated since the container can assume various shapes and sizes. In fact the filtering element B is designed to be placed inside a housing of irregular shape. On the other hand the pack may be of a given size to fit a standard oil refining casing that has an opening of the same size as the diameter of the container. The housings may be of various dimensions and the pack can be made of the required length and diameter to provide the proper amount of filtering material for the oil in the tank. The oil refining element B is therefore of a universal type since it may be inserted into housings of any dimension and contour and fill it partially or completely. In this respect the pack has a decided advantage over the rigid type pack because it can be fed into a container where the opening is not of the same diameter as the interior diameter of the container.

In use in airplanes the foldable pack has extreme practicability because the airplane oil tank may constitute the casing for the pack as well as the reservoir for oil. The only additional weight added to the airplane when adapting it to clean the oil is the weight of the pack itself. The pack is constructed from porous material which will become saturated with oil when in use and therefore the intrinsic weight of the pack is very slight. The pack does not displace much oil when saturated, so the tank need not be enlarged when using the pack. The tank A when supplied with a pack performs a double function of acting as an oil supply and also acting as an oil cleaner and refiner. A tank can only function in this manner when a flexible pack is used because the tank opening is so small in comparison to the tank diameter that a long pack must be used and the pack must be flexible and foldable in order to be fed into the tank.

In actual operation, the oil will be pumped into the tank A through the pipe 1 and will fill it. The oil will be forced through the pack body 13 for cleaning it. Foreign substances will be retained by the pack body. The loofah sponge 6 will remove the water from the oil and the fabric casing 10 and the screen 9 will form a flexible and porous wall for the central passage of the pack. The spring 6 keeps the fabric 10 and screen 9 in cylindrical form to provide an oil passageway. The oil passageway is flexible and has a density less than the density of the pack body 13. Of course the density of the passage is nil when it has no material therein. The cleaned oil once entering the central passage will flow therealong because it requires less force to move through the passage than through the pack body. The refined oil

passes through the pipe 7 and into the return pipe 5.

Should the pack become clogged for any reason the oil entering the tank through the pipe 1 would increase the pressure in the tank A until a point is reached sufficient to compress the spring 27. The ball 28 will be unseated by the increased oil pressure and the bypass C will permit the oil to flow directly into the pipe 7. The bypass prevents the tank A from being subjected to too great a pressure and permits the oil to continue to flow out through the pipe 5 should the pack become clogged for any reason and cease to function.

In Figure 4, I show a slightly modified form of pack B1. A rolled screen 6a takes the place of the spring 6 and the fabric 10a is wrapped around the screen to hold it in place. The screen 6a has one end inserted into the pipe 7, which end is held in place by the nails 8. All other parts of the pack are identical to that explained for the pack B; therefore further description need not be given. Like reference numerals will be applied to similar parts.

This flexible pack B1 will function in the same manner as the pack B shown in Figures 1 and 2. The screen 6a will form a central passageway having a density less than that of the pack body 13. If desired the screen 6a can partially fill the central passage without impeding the flow of oil through the passage because the oil can flow readily through the screen meshes. On the other hand the screen is preferably rolled into a cylinder that forms a central passage which is free from any obstruction. The rolled screen 6a is flexible and supports the pack body 13, loofah sponge 11 and fabric 10a.

Another modified form of pack B2 is illustrated in Figure 5. Here the central passage of the pack is formed by a flexible conduit 6b that has openings 32 formed therein. A screen 9 covers the conduit and is in turn covered by the fabric 10. The flexible conduit 6b has one end inserted in the pipe 7 which is secured in place by nails 8 that extend at right angles to each other. The flexible conduit acts as a flexible central sustaining member for the pack body. All other parts of the pack are identical to those described and illustrated in Figure 2. Like reference numerals will be applied to similar parts and further description need not be given.

In neither Figures 4 or 5 do I show the free end of the pack as I do in Figure 2. In both modified forms of pack B1 and B2, the central conduits are flattened at their free ends and so also are the screen, fabric and sponge. Heavy absorbent twine is wrapped around the flattened portions in the same manner as I have indicated in Figure 2. In fact, the free ends of the forms of the packs B1 and B2 are the same as that shown in Figure 2 except that in the pack B1, the screen 6a takes the place of the spring 6 and in the other pack B2, the flexible conduit 6b takes the place of the spring 6. A modified form of pack B1 or B2 may be placed in the tank A or in any other container and function in the same manner as that set forth for the pack B.

Although the oil may flow in a reverse direction through the packs, I do not advocate such use because the internal pressure will have a tendency to burst the pack and the binding 16 would need to be made stronger. The vital point is the provision of a flexible central sustaining member for the pack body with an oil passageway in the pack body of less density than the body proper. Such

a pack can be inserted in containers of every conceivable shape and size. A portion of the high pressure oil system for a machine or engine can constitute the casing for the flexible and foldable pack. Very little additional weight is added when using the pack in a part of the oiling system and no additional space is required.

In Figures 6 and 7 I show another modified form of pack where an alkali has been added to the pack body to keep the oil neutral as well as to cleanse the oil as it flows through the pack. The oil at the refinery is neutralized as to acidity by adding an alkali. The oil to be neutral should have a pH value of 7. When oil is used in an engine it becomes acid in reaction because the acid is formed as a product of combustion. The oil at the top of the cylinders and the motor fuel burned in the cylinders form acids which draw in down around the piston walls and find their way into the body of oil. The moisture resulting from condensation or from leaky gaskets enters the crank case and through agitation mixes with the acids in the oil to form a sulphurous acid which has a corrosive effect on the metal.

Long use of the automobile or tractor engine for ten thousand to twenty thousand miles causes an acidity of the oil which when combined with the moisture might harm the engine. It is therefore a part of my invention to provide a pack with an alkali so that the pack will not only keep the oil visually clean but will also neutralize the acid content of the oil. The alkali used for this purpose may be sodium carbonate, potassium carbonate, or any alkali having the ability to neutralize acidity in oils. In fact any alkali having the ability to neutralize acids in an oil comes within the scope of my invention.

A pack when used for cleaning oil becomes contaminated with foreign matter after a time. It is therefore necessary that the pack be renewed from time to time. The alkali in the pack will neutralize the acid condition of the oil and as the pack becomes older, the alkali will be used up so that acidity of the oil will rise. I prevent this acidity from reaching dangerous proportions by renewing the pack and the new pack will have sufficient alkali therein for neutralizing the oil. The packs perform the dual function of removing contaminants from the oil and keeping the oil neutral. Diesel engines form acid oil more quickly than engines using gasoline as a motor fuel.

Strongly basic materials such as sodium hydroxide or potassium hydroxide cannot be used as an alkali in the pack because the chemicals are too caustic in nature and would even injure the cellulosic portions of the pack. Referring to Figures 6 and 7 it will be noted that the pack structure B³ is the same as that shown in Figure 2 except that an alkali treated strip 50 forms a part of the body 13 of the pack. The strip or layer 50 is formed into a cylindrical portion and takes up approximately the middle third of the cellulosic pack fabric. The layer 50 may be impregnated with the alkali by saturating the layer with the alkali solution or by placing the alkali in crystalline form in the layer. In all other respects the structure of the pack shown in Figures 6 and

7 is the same as that shown in Figure 2 and therefore further description need not be given and corresponding parts will be given like reference numerals.

I do not wish to be confined to the layer 50 taking up the middle third of the cellulosic body since the pack body might be treated throughout with an alkali or be partially treated and the treated portion be in some other position than the middle third, disclosed in Figure 6. For example, the alkali treated layer may be on the outside of the pack or in the very inside of the pack. It could be placed at the top or at the bottom of the pack. All of these various modifications are deemed to come within the scope of the appended claim.

I claim:

A fluid filtering pack having a flexible hollow core acting as a fluid passageway, a pipe communicating with one end of the core, flexible screening means enclosing the core, a layer of sponge enclosing said screening means, a fluid absorbent cord wrapped around the screening means, sponge and pipe for connecting them together, a second fluid absorbent cord wrapped around the free end of the screening means and sponge to close the free end of the core, a flexible pack body formed of three layers of filtering material and enclosing the screening means and cord wrappings and having a substantial depth between the screen and the outer surface of the pack, the center layer of said pack body being alkali-impregnated for neutralizing any acid condition of the oil flowing through the body, a fabric casing enclosing the entire pack assembly, said casing being wrapped at each end with string.
